UNITED STATES PATENT OFFICE.

HERMANN SIEGEL, OF NEW YORK, N. Y.

DESIGN FOR A GLASS VESSEL.

SPECIFICATION forming part of Design No. 23,727, dated October 23, 1894.

Application filed September 24, 1894. Serial No. 523,983. Term of patent 7 years.

To all whom it may concern:

Be it known that I, HERMANN SIEGEL, of New York, in the county of New York and State of New York, have invented and produced a new and original Design for Glass Vessels, of which the following is a specification, reference being had to the accompanying drawings, in which—

Figure 1—is a plan view of a dish ornamented with my design, and Fig. 2—represents a cross sectional view of the same.

The leading feature of my design consists of four pairs of parallel grooves crossing and forming substantially a square at the center and extending from such square about to the edge of the dish, and one pair of parallel grooves surrounding the square about midway between it and the edge of the dish.

In the design as represented in the accompanying drawings, the four pairs of parallel grooves *a* cross near the center of the dish, and form substantially a square, while each two pairs of parallel grooves extending beyond each corner of the square, are curved slightly toward each other. A pair of grooves *b* surround and inclose the square and form a circle around it at a point slightly beyond the midway distance to the edge of the dish. The two deep grooves forming each pair so far described, are connected by small round-bottom grooves producing a bead appearance.

The corners of the central square are crossed by pairs of straight grooves *c* which extend to the grooves *a* a short distance beyond the corners of said square. These grooves *c* therefore form a second square at an angle of forty-five degrees from the first. The field inclosed by the squares may be occupied by a conventional rosette. Two single grooves *d* crossing each other at the grooves *b*, connect each pair of parallel grooves *a* near the edge of the dish, and the fields or spaces between the several deep grooves described are occupied by rosettes and sprays of smaller grooves. These rosettes and sprays are omitted from some of the fields in the accompanying drawings, in order to more prominently illustrate the leading features of the design; but it is to be understood that the fields unoccupied in the drawings will, in practice, be ornamented by rosettes and sprays duplicates of those shown.

Having thus described my invention, what I claim is—

The design for glass vessels substantially as herein shown and described.

In testimony whereof I affix my signature in presence of two subscribing witnesses.

HERMANN SIEGEL.
